UNITED STATES PATENT OFFICE.

CHARLES W. TURNER, OF BROOKLYN, NEW YORK.

OXYHYDROCARBON-BURNER.

1,097,066.

Specification of Letters Patent. Patented May 19, 1914.

Application filed December 31, 1912. Serial No. 739,567.

To all whom it may concern:

Be it known that I, CHARLES W. TURNER, a citizen of the United States, residing at Brooklyn, in the county of Kings and State 5 of New York, have invented certain new and useful Improvements in Oxyhydrocarbon-Burners, of which the following is a specification.

This invention relates to apparatus for 10 generating and burning oxyhydrocarbon vapor or gas, containing oxygen, hydrogen and carbon, from a mixture of water and hydrocarbon oil, for heating steam-boilers, metallurgic furnaces, gas generators, domestic furnaces and other devices where a 15 high heat is required.

The object of my invention is to provide, more particularly, for burning petroleum or other heavy hydrocarbon oil, by causing 20 decomposition thereof in combination with water and recombination of the elements to form oxyhydrocarbon gas under high heat and pressure—the gas being of high calorific value.

25 One of the special objects is to provide for separating, depositing and discharging earthy matter, asphaltum and other dense carbonaceous matter from the oil or vapor during the generating and burning operation, so that no part of the generating coils or burners shall become clogged or obstructed, and so that a continuous strong flame and perfect combustion may be produced.

35 This invention is an improvement on the oxyhydrocarbon burner forming the subject of Letters Patent No. 746,409 granted to me December 8, 1903. The apparatus described in this patent has been in successful operation 40 for a number of years, using kerosene or a similar distillate hydrocarbon oil, but I have found that it was not adapted for using petroleum or other heavy hydrocarbon by reason of the formation of deposits 45 of asphaltum or other dense carbonaceous matter in the interior of the coils, thus obstructing them and stopping the generation and flow of gas or vapor to the burners. In order to overcome this difficulty I provide 50 and connect with the sections of coils, at a number of points, separating drums of larger diameter than the coils and having deposit pockets in which the dense carbonaceous matter is deposited, and from which it may 55 be drawn or blown off as required for keep-

ing the coils, pipes and burners free from obstructions.

While my burner apparatus is designed and adapted for effectively utilizing petroleum and other cheap heavy oil for combustion, it can be used with equally economical results in burning kerosene or other intermediate oils.

The matter constituting my invention will be defined in the claims.

I will now describe the details of construction of my oil burning apparatus by reference to the accompanying drawings, in which—

Figure 1 represents a side elevation with parts in vertical section, and with parts of the generator diagrammatically arranged for more clearly showing the separating drums. Fig. 2 represents an elevation of the vaporizing and generating coils and the separating drums compactly arranged in proper relation one to another for effective operation.

The vaporizing and generating coils 1 of 80 my oxyhydrocarbon-burner apparatus are located in the fire-box of a steam boiler 2 or other furnace where a high heat is required. The coils are divided into sections, between which are interposed separating and depositing drums, one drum between each pair of coil-sections and a drum between the last coil-section and the burners, as will be described in detail below.

The oil supply tank 3 and water supply tank 4 will be mounted on a suitable support 90 at any convenient distance from the generator and burner apparatus and are shown connected at their lower ends with a water-force pump 5, the discharge pipe 6, having a valve 7, connecting with tank 4, and a branch pipe 8, having a valve 9, connecting with tank 3. This water force pump is one of a number of devices which may be used 95 for forcing water and oil under pressure into the vaporizing and gasifying coils. The liquid may be forced by air admitted under pressure at the tops of the tanks, in a well-known manner. Before admitting water into tank 3, valve 9 being closed, the tank is filled with petroleum or other heavy 100 hydrocarbon oil, and then when it is desired to force oil into the generating coils, the valve 9 will be opened, admitting water under pressure below the body of oil. The oil feed pipe 10 connects with the top of tank 3 110

and with the middle portion of the heating and separating drum 15 located within the coils 23 and 26. Pipe 10 is provided with stop valves 11 and 13, an intermediate check-valve 12 and a test cock 14. An oil vapor pipe 16 leads from the top of drum 15 to a T-fitting 16^a, with which a steam pipe 22 also connects, at the inlet of the mixing coil 23. With the top of water tank 4 connects 10 a feed-pipe 17 leading to the base of the water heating or steam generating drum 18, from the top of which leads a pipe 22 to the T-fitting 16^a. The feed-pipe 17 is provided with stop-valves 20 and 20^a, an intermediate check valve 19 and a test cock 21.

In order to determine the rate of flow and quantity of oil supplied through feed pipe 10, the valve 13 is closed, the test cock 14 fully opened, and the valve 11 partly 20 opened and adjusted, so that the desired flow will be discharged through the test cock. This having been ascertained by observation, the test cock 14 is closed and valve 13 opened, leaving valve 11 at the proper 25 adjustment for feeding the desired quantity or proportion of oil into the heating and separating drum 15. The flow of water through pipe 17 will be controlled and the proportion determined by means of test 30 cock 21 and adjustment of valve 20 in the manner above described with reference to the oil feed pipe.

I have found that satisfactory results may be obtained by dividing the coil of pipe, in 35 which oxyhydrocarbon gas is generated, into four sections or sets, as 23, 26, 29 and 32, and connecting the outlet of one coil section and the inlet of a succeeding coil section with an interposed separating and 40 depositing drum for collecting and discharging asphaltum or other dense carbonaceous matter. The mixing coil 23, in which steam and oil vapor are mixed, connects at its inlet end with T-fitting 16^a and at its outlet 45 end with the middle portion of a separating and depositing drum 24. An outlet pipe 25 leads from the top of drum 24 to the inlet end of coil section 26, from the lower end of which an outlet pipe connects with the middle portion of a separating and depositing 50 drum 27. The coil section 26 is called the combining and superheating coil. An outlet pipe 28 leads from the top of drum 27 to the inlet end of the decomposing coil section 29. The outlet end of this coil connects with the middle portion of a separating and depositing drum 30, from the top of which a pipe leads to the inlet end of the decomposing and recomposing coil section 32. The outlet end of this coil connects with the middle portion of the separating and depositing drum 33, from the top of which extends the outlet gas pipe 34, which connects at its lower end with the 65 horizontal gas pipe 35 connecting at both

ends with the burners 36. Auxiliary smaller burners 37, 37, are connected with the gas pipe 35 and placed adjacent to the main burner 36. This provision is made so that if either one of the main burners becomes accidentally extinguished, as sometimes happens, it will be re-lighted by one of the auxiliary burners.

Each of the separating and depositing drums 15, 24, 27, 30 and 33 is provided with a pocket 38 at its lower end, for receiving asphaltum, tarry matter and other dense carbonaceous matter. The burners 36 are also provided with depositing pockets below the inlet gas pipes 35. With the bottom of each pocket is connected a discharge or blow-off pipe 40, each having a valve 42, and each connecting with a drain pipe 43 leading to a receiving tank 44. Whenever it appears from the condition of the flame 85 at the burners that any pipe or drum is becoming obstructed, any one or more of the valves 42 may be opened, permitting the heavy residuum or carbonaceous matter to be blown out and discharged into the receiving tank.

The coils may be maintained at a temperature between 800° F. and 1500° F., and the oil and water may be forced into their respective drums at a pressure between fifty 95 and seventy pounds, and in the proportion of three parts of oil to one of water, or four parts of oil to one of water. The proportions, however, of oil and water may be varied within wide limit, according to the 100 character of heat required and to the quality of oil used.

With a comparatively high heat and slow feed of oil to the drum 15, most of the lighter oils will be vaporized therein and the 105 vapor passed over into the mixing coil 23, but if the temperature falls or the feed of oil is relatively increased, part of the lighter heated oil may flow over into the mixing coil 23, or to the T-fitting 16^a, where the 110 current of steam would atomize it. In either case the earthy and tarry matter will be first separated from the oil and deposited in the pocket at the lower end of drum 15. Vaporization of the oil will be completed in 115 coil 23.

In putting the apparatus in operation, the oil and water tanks are first filled, the pump put into operation, and the relative flow of the oil and water through each feed pipe is 120 adjusted as above described. Some kind of oily waste may be first burned in the fire box below the coils for heating them to a sufficient temperature to vaporize oil. A small flow of oil is then first admitted into 125 drum 15, where it is vaporized and the vapor forced through all of the coil sections to the burners. After the heat is sufficiently raised, a small flow of water is admitted into the drum 18, where steam is generated. The 130

flow of oil will be gradually increased until strong flames are produced at the burners, and until the coil sections 29 and 32 are heated to approximately 1000° F. The full 5 supply of oil and water may now be fed under pressure to their respective drums. The proper flow of oil and water having been established for producing strong flames which pass up through the coils, very little 10 attention will be required to keep the burner in successful operation. The mixed and heated vapors of oil and water, passing from coil 23 will be passed from drum 24 into coil section 26, where the vapors will be combined and superheated nearly to the point of 15 decomposition. The combined vapors will pass from drum 27 into coil section 29, where decomposition is partially effected, and the resulting gaseous products will be discharged into drum 30 and passed therefrom into the coil section 32, where decomposition and re-composition are completed, resulting in the production of oxyhydrocarbon gas, which after passing through 20 drum 33 is supplied to the burner 36. In the coil sections 29 and 32, part of the oxygen of the steam combines with part of the carbon of the oil to form carbon monoxide, while the hydrogen of the water is set free. 25 The combined gases containing oxygen, hydrogen and carbon, in a highly heated state, give a very high flame temperature at the burner. Thus highly economical results are produced in the combustion of petroleum or 30 other cheap, heavy hydrocarbon oils.

The pressure in the oil and water tanks will be registered by gages α and γ applied to the outlet pipes 10 and 17, as shown, or directly to the tanks.

Having described my invention, what I claim, and desire to secure by Letters Patent, is:

1. In an oxyhydrocarbon-burner apparatus, the combination with a coil through 45 which hydrocarbon vapor is forced, of a heating and separating drum in which heavy carbonaceous matter is separated from the lighter hydrocarbon, an oil feed pipe connecting with the middle part of said drum 50 and an upper outlet pipe leading from the drum to said coil, whereby the pipes and coil may be kept free from obstructions, and a suitably connected burner for burning the gas generated and projecting a flame upon 55 the coil.

2. In an oxyhydrocarbon-burner apparatus, the combination with a mixing coil for oil and water vapor and one or more connecting superheating and decomposing coils, 60 of a separating and depositing drum, having a discharge pipe and valve for drawing off heavy carbonaceous matter, an oil feed pipe connecting with the drum above said discharge pipe, an upper outlet pipe connecting the drum with said vapor-mixing

coil, a steam supply pipe also connecting with said vapor mixing coil, and a burner connecting with a superheating coil to direct a flame in contact with the coils.

3. In an oxyhydrocarbon-burner apparatus, the combination with a vapor-mixing coil having supply pipes for oil and water vapors, of combining, superheating and decomposing coil sections, an interposed separating and depositing drum having a pocket 70 for receiving asphaltum or other heavy carbonaceous matter, between two connecting coil sections, an inlet pipe connection from one coil section to the middle portion of the interposed drum, and an outlet pipe from 75 the top of the drum to the other coil section, and a burner connecting with a superheating and decomposing coil and so disposed as to direct a flame in contact with the coils.

4. In an oxyhydrocarbon-burner apparatus, the combination with two sets or sections of combining and superheating coils for oil and water vapors of an interposed separating and depositing drum, an inlet pipe connecting the discharge end of one 80 coil section with the middle portion of the drum, and an outlet pipe from the top of the drum connecting with the inlet of the other set of coils, and a burner supplied from said coils, whereby asphaltum or tarry matter 85 may be deposited in the drum and discharged, so as to keep the coils and burner 90 free from obstructions.

5. In an oxyhydrocarbon-burner apparatus, the combination with a vapor mixing 100 coil, a steam generating drum connecting with said mixing coil, a combining and superheating coil for oil vapor and steam, and connections from said vapor mixing coil to the superheating coil, of an oil heating and separating drum having a deposit pocket for heavy carbonaceous matter and a top outlet pipe leading to said vapor mixing coil, a second separating drum connecting with the outlet of said superheating coil, 105 110 a decomposing coil connecting with the top of the second drum and burners, connecting with said decomposing coil.

6. In an oxyhydrocarbon-burner apparatus, the combination with two adjacent sections of coils, of an upright separating drum having a deposit pocket and a bottom draw-off pipe for heavy carbonaceous matter, the outlet pipe of the first section connecting with the middle portion of the drum, and 115 the inlet pipe of the second section connecting with the top of the drum, whereby asphaltum or tarry matter may be deposited and blown off from the pocket for keeping the coils free from obstructions.

7. In an oxyhydrocarbon burner apparatus, the combination with a water heating drum having a supply pipe and an oil-heating and separating drum having a bottom pocket and discharge pipe for heavy carbo-

naceous matter, and a supply pipe connecting with its middle portion, of a vapor mixing coil, a fitting at the inlet end thereof, pipes connecting said oil and water drums with said fitting, a combining and superheating coil connected to the vapor-mixing coil, and decomposing coils connected in series beyond said superheating coil, a separating and depositing drum being interposed between each pair of coils and connected at its middle portion with the outlet

of the preceding coil and at its upper portion with the inlet of the succeeding coil, and a burner connected to the last of said coils.

15

In testimony whereof I affix my signature in presence of two witnesses.

CHARLES W. TURNER.
